DRAFTING MECHANISM FOR SPINNING MACHINES

Erwin Dausch, Esslingen Neckar, Germany, assignor to SKF Kugellagerfabriken G. m. b. H., Schweinfurt, Germany

Application December 8, 1955, Serial No. 551,782

Claims priority, application Germany December 18, 1954

13 Claims. (Cl. 19—135)

The present invention relates to drafting mechanisms used in textile machines to treat the yarns just before they reach the spinning part of a spinning machine.

As is well known, such drafting mechanisms include pairs of top and bottom rolls which nip the yarns as they move along the drawing plane. Although many structures are known for supporting the top rolls of such a drafting mechanism, such structures are in general fairly costly and complicated.

One of the objects of the present invention is to provide an exceedingly simple structure for carrying the top rolls of a drafting mechanism.

Another object of the present invention is to provide a drafting mechanism where the elements which carry the top rolls have a minimum amount of connections to other elements and are provided with a high degree of freedom of movement.

A further object of the present invention is to provide a top rolls carrying structure which is characterized not only by great simplicity but also by extreme ruggedness of construction and reliability in operation.

With the above objects in view the present invention mainly consists of a drafting mechanism which includes a frame means and an elongated support means carried by the frame means for movement to and from an operating position. An arm means is carried by the frame means for carrying the top rolls themselves, and this arm means includes at least a pair of top rolls carrying arms which are linked together. A means is provided for urging the arms downwardly toward the drawing plane when the support means is in its operating position.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a partly sectional side elevational view of a drafting mechanism according to the present invention, the upper portion of Fig. 1 being shown in section and the section of Fig. 1 being taken along line 1—1 of Fig. 2 in the direction of the arrows;

Fig. 2 is a sectional plan view taken along the line 2—2 of Fig. 1 in the direction of the arrows;

Fig. 3 is a transverse sectional view taken along line 3—3 of Fig. 1 in the direction of the arrows;

Fig. 4 is a fragmentary sectional view taken along line 4—4 of Fig. 1 in the direction of the arrows;

Fig. 5 is a fragmentary sectional view taken along line 5—5 of Fig. 1 in the direction of the arrows;

Fig. 6 is a sectional elevational view of a top rolls carrying arm provided with a means for adjustably positioning the top rolls carried thereby;

Fig. 7 is a diagrammatic illustration of a variation of the top rolls carrying structure of the invention; and

Fig. 8 is a diagrammatic illustration of still another

2

embodiment of a top rolls carrying structure according to the present invention.

Referring now to the drawings and to Figs. 1—5 in particular, it will be seen that a stationary frame 10 of conventional construction is provided. This frame 10 carries in a known way the bottom rolls 27, 27a, and 27b. At its rear end portion the frame 10 carries a pivot pin 12, and an elongated support 11 is pivotally connected at its rear end portion to the frame 10 through the medium of the pivot pin 12, this elongated support 11 being turnable upwardly from the operating position shown in Fig. 1 to an inoperative position and then back again to the operating position illustrated in Fig. 1.

The elongated support means 11 is in the form of an elongated channel member of U-shaped cross section which is open at the bottom, as is clearly illustrated in Fig. 3. Furthermore, as is evident from Figs. 1, 2, and 5, the frame 10 is provided with a pair of upwardly extending ears between which the pivot pin 12 extends, and the support 11 is located at its rear end portion between these ears, the support having at the rear portion of its side walls a pair of inwardly extending hubs 20 through which the pivot pin 12 passes, as is shown most clearly in Fig. 5.

A conventional means is provided for releasably holding the support means 11 in its operating position, and this means includes the catch member 14 which is substantially U-shaped and which has a top leg extending across the top of the support 11 and a pair of side legs extending downwardly along and beyond the sides of the support 11, these legs terminating in the hook portions 18 one of which is shown in Fig. 1. The member 14 is provided at its top portion with a downwardly extending lug 15 which extends freely through an opening 16 formed in the top wall of the elongated support 11, this lug 15 being

formed with an opening through which a wavy leaf spring 17 passes, as shown in Fig. 1. This leaf spring 17 engages the underside of the top wall of the support means 11, and urges the catch 14 in a counterclockwise direction, as viewed in Fig. 1, the catch 14 having at its top leg a concave underside which engages a convex projection of the support 11, as shown in Fig. 1, so that in this way the catch 14 is pivotally carried by the support 11 within the limits of freedom provided by the lug 15 within the opening 16. In order to release the support means 11 for movement to its inoperative position, it is only necessary to turn the catch 14 in a clockwise direction slightly, against the influence of the spring 17, so as to disengage the hook portions 18 from the stationary projections 19 of the frame means 10 which respectively cooperate with the hook portions 18, as is clearly evident from Figs. 1 and 2.

Then the support means 11 may be turned upwardly towards its inoperative position. In returning the support means to its operating position, the hook portions 18 simply ride over the projections 19 and snap under the same in order to releasably hold the support 11 in the operating position thereof shown in Fig. 1.

In accordance with the present invention a top rolls carrying arm means is provided to carry the top rolls, and this arm means is in turn connected to the support means 11 for movement therewith to and from its operating position. The top rolls carrying arm means includes an elongated rear arm 22 which is located between the side walls of the support means 11 and which has a rear end portion 21 formed with a bore through which the pivot pin 12 extends, so that the rear top rolls carrying arm 22 is turnable with the support means 11 about the pin 12 and at the same time is turnable with respect to the support means 11 about the pin 12. As is shown most clearly in Fig. 5, the bore of the rear portion 21 of the top rolls carrying arm 22 through which the pivot pin 12 passes is not cylindrical. Instead this bore has a minimum diameter at its central portion

and becomes gradually wider towards its ends so that the arm 22 may tilt to a certain degree laterally with respect to the pivot pin 12 in a direction parallel to the drawing plane. At its forward portion the arm 22 is fixedly connected to a saddle 23, as by being formed integrally therewith, and the shaft 25 of a pair of top rolls 26 which cooperate with the bottom rolls 27 is in operative engagement with the saddle 23. A spring 24 fixed to the saddle 23 maintains the shaft 25 in its operating position in a well known manner. At its forward end the top rolls carrying arm 22 is provided with a pair of forwardly extending ears 33 which are laterally spaced from each other and which carry a pivot pin 34 which extends between the ears 33. A second top rolls carrying arm 22a is provided at its rear end portion with a bore through which the pivot pin 34 passes, so that in this way the top rolls carrying arm 22a is pivotally linked to the top rolls carrying arm 22 and extends forwardly from the same.

A spring 32 is located between and engages the support 11 and the arm 22, in the manner shown in Fig. 1, to urge the arm 22 downwardly toward the drawing plane when the support 11 is in the operating position shown in Fig. 1, in order to provide the desired pressure between the top rolls 26 and the cooperating bottom rolls 27. A stop member 28 of substantially L-shaped cross section is fixed to the arm 22, as by being formed integrally therewith, and extends upwardly therefrom in the manner shown in Fig. 1, the stop member 28 having at its top portion a forwardly extending projection 29. A second stop member 31 is fixed to the support 11 as by being formed integrally therewith, and this stop member 31 also is of a substantially L-shaped construction and has a rearwardly extending projection 30 located beneath the projection 29 in the manner shown most clearly in Fig. 1. Thus, when the support means 11 is turned upwardly to its inoperative position, the projection 30 which is located in the path of movement of the projection 29 will engage the latter and in this way limit the downward movement of the top rolls carrying arm 22 with respect to the support 11.

The construction of the top rolls carrying arm 22a is substantially the same as that of the top rolls carrying arm 22, and the corresponding parts are indicated with the same numerals designating the parts associated with arm 22 followed by the letter *a*. Thus, it will be seen that the arm 22a is fixed to a saddle 23a which operatively engages a shaft 25a of a pair of top rolls 26a which respectively cooperate with the bottom rolls 27a, the spring 24a retaining the shaft 25a in its operative position with respect to the saddle 23a. Furthermore the spring 32a urges the arm 22a downwardly toward the drawing plane in the operating position of the parts shown in Fig. 1, and the stops 28a, 29a and 30a, 31a limit the downward movement of the arm 22a with respect to the support means 11 when the latter is turned upwardly to its inoperative position.

The arm 22a also is provided with a pair of forwardly extending ears 33a which carry a pivot pin 34a, and the forwardmost top rolls carrying arm 22b of Fig. 1 is pivotally carried at its rear end portion by the pivot pin 34a, the structure of arm 22b and the parts cooperating therewith being identical with the corresponding elements of arms 22 and 22a and being indicated with the same numerals followed by the letter *b*, as is indicated in Fig. 1. It will be noted that the arm 22b differs from the other arms solely by the fact that the arm 22b is not provided with any forwardly extending ears since it is itself the foremost arm. The front end of the arm 22b terminates in a stop member which cooperates with a rearwardly extending projection of the front wall of the support 11 to limit the downward movement of the arm 22b with respect to the support 11, when the latter is turned upwardly to its inoperative position.

The manner in which the springs 24, 24a, and 24b

are connected to the saddles is clearly illustrated in Fig. 3, which also illustrates the width of the stops 31, 31a with respect to the support means 11. Furthermore, Figs. 1 and 3 clearly show the top wall 13 of the support means 11 to which the stops 31 and 31a are fixed and through which the lug 15 of the catch 14 extends.

As is clearly evident from Fig. 4, the bores at the rear end portions of the arms through which the pivot pins respectively extend are not cylindrical. Although this structure is shown in Fig. 4 only with respect to the connection between the arms 22a and 22b, the same structure is located at the connection between the arms 22 and 22a. Thus, as may be seen from Fig. 4, the bore at the rear end portion of arm 22b has a minimum diameter at its central part and gradually becomes wider toward its ends so that in this way the top rolls carrying arms have a limited degree of free lateral movement. Thus, the top rolls are capable of automatically aligning themselves with the bottom rolls.

Fig. 2 clearly illustrates the manner in which the top rolls are distributed with respect to the support 11, and furthermore Fig. 2 clearly shows how the springs 32, 32a, and 32b act on the top rolls carrying arms.

With the above described structure the saddles 23, 23a, and 23b are rigidly fixed to the top rolls carrying arms, respectively, so that it is not possible to adjust the position of the top rolls along the top rolls carrying arms, respectively. However, under certain circumstances the bottom rolls are adjustable along the drawing plane, and it is therefore desirable to be able to adjust the position of the top rolls with respect to their arms so that the top rolls may cooperate properly with the bottom rolls. Fig. 6 shows a structure capable of accomplishing this result. Thus, Fig. 6 shows a top rolls carrying arm 40 which may replace any or all of the top rolls carrying arms described above. That is, one or more of the top rolls carrying arms 22, 22a, and 22b may be replaced by an arm 40 as shown in Fig. 6. This arm 40 is identical with the above described top rolls carrying arms to the extent that the arm 40 has an elongated portion 41 whose rear end portion 42 is provided with a bore as illustrated in Fig. 4 or 5 through which a pivot pin passes. Furthermore the arm 40 is provided with a stop member 44, 45 identical with the stop member 28, 29, and the arm 40 has a pair of forwardly extending ears 43 adapted to carry a pivot pin for linking the arm 40 with another arm 40 which extends forwardly from the same.

However, the arm 40 does not directly carry the top rolls through the medium of a saddle which is integral with the arm 40. Instead a screw 47 is threadedly connected to the arm 40 and passes through a slot 48 of a saddle carrying member 46. This slot 48 is of a smaller width than the head of the screw 47, so that this screw 47 may be turned in one direction to loosen the connection between the saddle member 46 and in another direction to fix the adjusted position of the saddle member 46 with respect to the arm 40. The saddle member 46 has a forward saddle portion 49, and a spring 50 is provided to maintain the top rolls in their operative position in the saddle portion 49.

It will be noted that with the above described structure, as is most clearly evident from Fig. 1, all of the top rolls carrying arms 22, 22a, and 22b are in a common plane when the support means 11 is in its operating position, and this plane is substantially parallel to the drawing plane. However, it is also possible in accordance with the present invention to locate the top rolls carrying arms in positions inclined to the drawing plane, and such a variation is illustrated diagrammatically in Figs. 7 and 8. Thus, as may be seen from Fig. 7, the support means 11c which is pivotally connected to the frame means in the same way as the support means 11 is pivotally connected at its rear end to a top rolls carrying arm 50. This top rolls carrying arm 50 is in turn pivotally connected at its forward end to a top rolls carrying arm 50a, and the top rolls

carrying arm 50a is pivotally connected at its front end to a top rolls carrying arm 50b. These top rolls carrying arms differ from those described above in that they are inclined with their rear ends located higher than the front end portions thereof to which the saddle members are fixed in the manner shown diagrammatically in Fig. 7. The front end of the arm 50 is provided with a pair of ears which extend upwardly with respect to the remainder of the arm 50 and which carry a pivot pin extending between these ears and pivotally supporting the rear end portion of the arm 50a which is also provided with a pair of upwardly extending ears at its front end which carry a pivot pin to which the rear end of the arm 50b is pivotally connected. As is shown diagrammatically in Fig. 7, the stop means for limiting the movement of the arms 50, 50a, and 50b with respect to the support means 11c is substantially identical with the stop means described above. The remaining structure which is not illustrated in Fig. 7 is identical with that described above. Thus, the same or substantially similar springs may be used for urging the arms of Fig. 7 downwardly with respect to the drawing plane, and the bottom roll carrying structure and frame for supporting the support means 11c may be identical with that of Fig. 1.

Fig. 8 shows an embodiment where the top roll carrying arms have front end which are located higher than their rear ends. Thus, the support means 11d which corresponds to the support means 11c is pivotally connected at its rear end to an arm 60 fixed to a saddle for carrying the rear top rolls. The arm 60 is provided at its front end with a pair of downwardly extending ears which carry a pivot pin extending between these ears, and the rear end portion of the top rolls carrying arm 60a is pivotally connected to this pivot pin. The arm 60a is in turn provided at its front end with a pair of downwardly extending ears between which extends a pivot pin which serves to pivotally interconnect the rear end of the top rolls carrying arm 60b with the front end of the arm 60a. Except for this variation the structure of Fig. 8 is identical with that of Fig. 7, and it is evident that with the embodiment of Fig. 8 the arms are inclined oppositely to the arms of Fig. 7.

Thus, it will be seen that with the structure described above an exceedingly simple and rugged arrangement is provided for supporting the top rolls of the drafting mechanism.

It will be understood that each of the elements described above, or two or more together, may also find a useful application in other types of drafting mechanisms differing from the types described above.

While the invention has been illustrated and described as embodied in top roll carrying structure of drafting mechanisms, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a drafting mechanism, in combination, frame means; elongated support means carried by said frame means for movement to and from an operating position located over the drawing plane; a first top rolls carrying arm pivotally connected at one end to one of said means; a second top rolls carrying arm extending forwardly from said first arm and having a rear end portion pivotally connected to a front end portion of said first

arm; and means engaging one of said arms for urging the same downwardly toward the drawing plane when said support means is in said operating position thereof.

2. In a drafting mechanism, in combination, frame means; elongated support means carried by said frame means for movement to and from an operating position located over the drawing plane; a series of top rolls carrying arms located one behind the other and linked adjacent their ends to each other, one of said arms being pivotally connected to one of said means; and means engaging said arms for urging the same downwardly toward the drawing plane when said support means is in said operating position thereof.

3. In a drafting mechanism, in combination, frame means; elongated support means carried by said frame means for movement to and from an operating position located over the drawing plane; a pair of top rolls carrying arms linked adjacent ends thereof to each other and located one behind the other in a common plane when said support means is in said operating position thereof, one of said arms being connected to one of said means; and means engaging said arms for urging the same downwardly toward the drawing plane when said support means is in said operating position thereof.

4. In a drafting mechanism, in combination, frame means; elongated support means carried by said frame means for movement to and from an operating position located over the drawing plane; a series of top rolls carrying arms located one behind the other and pivotally connected adjacent their ends one to another, one of said arms being pivotally connected to one of said means; and means engaging said arms for urging the same downwardly toward the drawing plane when said support means is in said operating position thereof.

5. In a drafting mechanism, in combination, frame means; elongated support means carried by said frame means for movement to and from an operating position located over the drawing plane; a pair of arms adapted to respectively carry top rolls pivotally connected adjacent their ends to each other, said arms being located one behind the other and one of said arms being connected to said support means; means engaging said arms for urging the same downwardly toward the drawing plane when said support means is in said operating position thereof; and stop means carried by said support means and said arms for limiting the downward movement of the latter with respect to one of said means.

6. In a drafting mechanism, in combination, frame means; elongated support means carried by said frame means for movement to and from an operating position located over the drawing plane; a plurality of top rolls carrying arms located one behind the other and pivotally connected adjacent their ends to each other, the rearmost of said arms being pivotally connected to said support means; means engaging said arms for urging the same downwardly toward the drawing plane when said support means is in said operating position thereof; and stop means carried by said support means and said arms for limiting the downward movement of the latter with respect to one of said means.

7. In a drafting mechanism, in combination, frame means; elongated support means carried by said frame means for movement to and from an operating position located over the drawing plane; a pair of arms located one behind the other and respectively having end portions linked to each other, one of said arms being connected to one of said means, and said arms being inclined to the drawing plane when said support means is in said operating position thereof; means engaging said arms for urging the same downwardly toward the drawing plane when said support means is in said operating position thereof; and stop means operatively connected to said support means and said arms for limiting the downward movement thereof with respect to said support means.

8. In a drafting mechanism, in combination, frame

means; elongated support means carried by said frame means for movement to and from an operating position located over the drawing plane; a pair of top rolls carrying arms pivotally connected adjacent ends thereof to each other and extending along said support means, one of said arms being pivotally connected to one of said means; means engaging at least one of said arms for urging the same downwardly toward the drawing plane when said support means is in said operating position thereof; and stop means connected to said support means and at least one of said arms for limiting the downward movement of said arms with respect to said support means.

9. In a drafting mechanism, in combination, a frame; an elongated support pivotally connected adjacent a rear end portion thereof to said frame for movement to and from an operating position located over the drawing plane; a first top rolls carrying arm pivotally connected at a rear end thereof to said support for movement about the same axis that said support turns about with respect to said frame; said first arm having a forwardly extending portion at the front end thereof; a second top rolls carrying arm having a rear end portion pivotally connected to said forwardly extending portion of said first arm and extending forwardly from the latter; means engaging said arms for urging the same downwardly toward the drawing plane; a first pair of stop members fixed to and extending from said first and second arms, respectively; a second pair of stop members fixed to said support and respectively located in the path of movement of said first pair of stop members when said support is moved away from said operating position thereof; and means for releasably holding said support in said operating position thereof.

10. In a drafting mechanism, in combination, frame means; elongated support means connected to said frame means for movement to and from an operating position located over the drawing plane; a first top rolls carrying arm having a rear end portion pivotally connected to one of said means and having a pair of forwardly extending ears; a pivot pin carried by and extending between said ears; a second top rolls carrying arm having a rear end portion pivotally carried by said pivot pin and extending forwardly from the latter; means engaging said arms for urging the same downwardly toward the drawing plane when said support means is in said operating position thereof; and stop means carried by said support means and arms for limiting downward movement thereof with respect to said support means.

11. In a drafting mechanism, in combination, a frame; a pivot pin carried by said frame at a rear end portion thereof; and elongated support pivotally connected at a rear end portion thereof to said pivot pin for movement with respect to said frame to and from an operating position located over the drawing plane; an elongated rear top rolls carrying arm also pivotally carried by said pivot pin;

5 a second top rolls carrying arm located forwardly of said rear arm and having a rear end portion pivotally connected to a front end portion of said rear arm; a pair of substantially L-shaped support members affixed to and extending upwardly from said arms; a pair of stop members fixed to said support and located in the path of movement of said L-shaped members for limiting the downward movement of said arms with respect to said support; and spring means engaging said arms for urging the same downwardly toward the drawing plane when said support is in its operating position.

12. In a drafting mechanism, in combination, frame means; elongated support means carried by said frame means for movement to and from an operating position located over the drawing plane; a first top rolls carrying arm having a rear end portion pivotally connected to one of said means and having a pair of forwardly extending ears; a pivot pin carried by and extending between said ears; a second top rolls carrying arm having a rear end portion formed with a transverse opening through which said pivot pin extends to pivotally connect said second arm to said first arm, said transverse opening having between its ends a substantially central portion of a minimum diameter and becoming gradually wider toward its ends so that said second arm may tilt laterally with respect to said first arm in a direction parallel to the drawing plane; and means engaging said arms for urging the same downwardly toward the drawing plane when said support means is in said operating position thereof.

13. In a drafting mechanism, in combination, frame means; elongated support means carried by said frame means for movement to and from an operating position located over the drawing plane; a first top rolls carrying arm pivotally connected at one end to one of said means; a second top rolls carrying arm extending forwardly from said first arm and having a rear end portion pivotally connected to a front end portion of said first arm; means engaging one of said arms for urging the same downwardly toward the drawing plane when said support means is in said operating position thereof; a saddle member located next to each of said arms; and adjusting means interconnecting each saddle member with each arm for adjusting the position of said saddle member longitudinally along said arm.
